[57] CLAIM

The ornamental design for a brassiere accessory, as shown and described.

DESCRIPTION

FIG. 1 is a perspective view of the brassiere accessory showing my new design in use;

FIG. 2 is a top view thereof.

FIG. 3 is a side view, the opposite side being a mirror image thereof; and,

FIG. 4 is a rear view thereof.

The broken line showing of environment in FIG. 1 is for illustrative purposes only and forms no part of the claimed design.
